UNITED STATES PATENT OFFICE.

ELMER E. McCULLEY, OF ST. LOUIS, MISSOURI.

ROTARY MOTOR.

1,239,412.

Specification of Letters Patent.

Patented Sept. 4, 1917.

Application filed December 18, 1914. Serial No. 877,879.

To all whom it may concern:

Be it known that I, ELMER E. McCULLEY, a citizen of the United States of America, and a resident of the city of St. Louis and State of Missouri, have invented certain new and useful Improvements in Rotary Motors, of which the following is a specification.

The primary object of this invention is to provide an improved type of rotary motor in which the cylinders thereof are arranged in pairs, each cylinder of each pair being arranged at an approximate right angle to the other.

Another object is to provide an improved motor with revolvably mounted cylinders, the pistons thereof being reciprocably mounted in said cylinders.

A further object is to provide an improved motor that is adapted to be operated by fluid pressure, in which there will be no dead center relative to the action of the pistons and ports.

A still further object is to provide this improved motor with a minimum number of parts.

Other and further objects will appear in the specification and be specifically pointed out in the appended claims, reference being had to the accompanying drawings exemplifying the invention, and in which,

Figure 1 is a plan view of this improved rotary motor.

Fig. 2 is a section taken through a pair of the cylinders and approximately on the line II—II, Fig. 1.

Fig. 3 is an enlarged horizontal section taken on the line III—III, Fig. 2.

Fig. 4 is a transverse section taken on the line IV—IV, Fig. 1.

Fig. 5 is a transverse section taken on the line V—V, Fig. 2.

Referring to the drawings: 1 designates the base which supports the standard 2.

Formed on top of said standard are a pair of bearings 3, said bearings having caps 4. Mounted in the bearings 3 is a horizontal shaft 5, one end of said shaft being mounted in the bearing 6. Mounted on one end of the shaft 5, and secured thereto, are a fly wheel 7 and a pulley 8.

Secured to said shaft between one of the bearings 3 and the bearing 6 is a member 9. Said member is arranged in a horizontal position and at right angles to a vertically arranged member 10. Said member 10 is revolvably mounted on the vertical post 11.

The upper end of said post is supported in the sleeve portion 12 of the bearing 6 and secured thereto by the pin 13. The lower end of said post is secured to, or formed integral with, a hollow member 14. This member 14 is mounted on a fluid chest 15, said chest having an inlet chamber 16 and an outlet chamber 17 formed therein.

Formed integral with the fluid chest 15 is a supply connection 18, said connection 18 having a fluid supply pipe 19 connected therewith. This supply pipe 19 leads to the inlet chamber 16, and to the chamber 20 formed in the hollow member 14. Formed on the fluid chest 15 is a pipe connection 21 which leads from the exhaust chamber 17. Mounted on said connection 21 is an exhaust pipe 22. This fluid chest 15 is seated on the seating portion 23 of the base portion 1 and standard 2, and is secured thereto by the bolts 24.

Formed in the member 9 are horizontally arranged cylinders 25, each of said cylinders having a closed end as indicated at 26. Formed in the member 10 are vertically arranged cylinders 27, each of said cylinders being closed at one end as indicated at 28. These cylinders are arranged in pairs, each of said cylinders 9 adapted to align with one of the cylinders 10. Reciprocably mounted in each pair of cylinders 9 and 10 is a piston 29. Each of said pistons comprises right angled bent portions 30 and 31. Each of the portions 30 of the pistons is mounted in a cylinder 25 of the member 9. Each of the portions 31 of the pistons is mounted in a cylinder 27 of the member 10. These pistons 29 are tubular in construction, there being a passageway formed therethrough from end to end. Carried by said pistons are packing rings 32.

Referring more particularly to Fig. 3, which is a horizontal section through the member 10, ports 33 are shown leading to the lower end of the cylinders 27. Formed in the wall of the hollow member 14, and leading from the chamber 20, is an opening 34, said opening 34 being in alinement with the ports 33. Formed in the wall of the member 14, opposite to the inlet opening 34, is a downwardly extending exhaust port 35, said exhaust port leading to the exhaust chamber 17 of the fluid chest 15.

In the operation of this improved rotary motor, when fluid under pressure is admitted to the inlet chamber 16 of the fluid

chest 15 and to the chamber 20, fluid pressure communication will be made to one of the inlet ports 33 of the member 10 through the opening 34, thereby creating a pressure in one of the cylinders 27. This pressure will also be communicated to one of the cylinders 25 through the respective piston 29. This will cause the pressure to bear against the ends 26 and 28 of a pair 10 of cylinders 25 and 27, thereby forcing the piston 29 from said cylinders. This action or reciprocation will revolve the members 9 and 10.

In order to make the operation more clear, 15 from an inspection of Fig. 3, it will be seen that the port 33, which is indicated by A, is receiving pressure from the opening 34, whereas the port B is in a position of exhaust, and the port C is cut off. Inasmuch 20 as the member 10 is revolved, upon reaching the edge D of the opening 34, the port C will begin to receive pressure until it reaches the edge E of said opening, and the piston operated in conjunction with said port will 25 travel on expansion from said edge E until the center line F is reached, after which the piston will be forced inwardly into its cylinders from said line F to the line G. As said port reaches the edge I, it is put in 30 a position of exhaust with the exhaust port 35 until the port passes the edge J of said exhaust port, said port C being ready for a fresh supply of pressure as it passes the line G. It is, therefore, seen how the ports A 35 and B will receive a like treatment as just described of the port C during each revolution of the member 10.

In a motor of this improved character, 40 as the pistons are forced outwardly from their respective cylinders, the members 9 and 10 will be revolved in a manner similar to a pair of bevel gears meshing together. As the member 9 is secured to the shaft 5, power can be transmitted from said shaft. 45 This construction of rotary motor is very simple, and there are but few parts, and practically any kind of pressure can be utilized to operate it.

What I claim is:

50 1. In a motor, a pair of revolvably mount-

ed members, a cylinder formed in each of said members, each of said cylinders being arranged at right angles to each other, a shaft for one of said members, a hollow post for the other said member, said shaft 55 having one end bearing on said post, and a piston having right angled portions, each of said portions of said piston being reciprocally mounted in each of said cylinders. 60

2. In a motor, a pair of revolvably mounted members, a plurality of cylinders formed in each of said members, said cylinders of one of said members being arranged at right angles to the cylinders of said other members, a plurality of pistons having 65 cylinder engaging portions adapted to engage each alining pair of said cylinders, a port for each cylinder formed in one of said members, a hollow post for one of said members, said ports adapted to communicate with said post, a shaft for said other member, and a bearing mounted on said post for the support of one end of said shaft. 70

3. In a motor, a pair of revolvably mounted members, a series of cylinders formed in each of said members, said cylinders being open at one end, said cylinders of each of said members having their open ends adjacent each other, said cylinders 80 of one of said members being positioned so as to aline with the cylinders of said other member, a hollow piston reciprocally mounted in each alined pair of said cylinders, each of said hollow pistons 85 providing means of communication from the closed end of one of said cylinders to the closed end of the other said cylinder of each of said pairs of cylinders, a hollow post extending into one of said members, a shaft 90 for said other member, said shaft being supported by said post, ports formed in said member of said post, said ports leading to said cylinders of said post member from said post. 95

ELMER E. McCULLEY.

In the presence of:—

H. G. FLETCHER,
M. C. HAMMON.
